UNITED STATES PATENT OFFICE.

ABRAHAM WITMER, OF HENRY, ILLINOIS.

IMPROVED BRICK-PRESS.

Specification forming part of Letters Patent No. 44,133, dated September 6, 1864.

To all whom it may concern:

Be it known that I, ABRAHAM WITMER, of Henry, in the county of Marshall and State of Illinois, have invented a new and Improved Brick-Press; and I do hereby declare that the following is a full, clear, and exact description thereof, which will enable others skilled in the art to make and use the same, reference being had to the accompanying drawings, forming part of this specification, in which—

Figure 1 is a side sectional view of my invention taken in the line $x x$, Fig. 2; Fig. 2, a horizontal section of the same taken in the line $y y$, Fig. 1; Fig. 3, a transverse vertical section of the same taken in the line $z z$, Fig. 1.

Similar letters of reference indicate like parts.

This invention relates, first, to a new and useful improvement in the pressers for forcing the clay into the molds, whereby the former are rendered much more efficient than usual in consequence of not being allowed to carry the clay around with them in the mud-mill. The invention relates, second, to an improved means for forcing the filled molds out from underneath the mud, and also to an improved arrangement of rollers for insuring the easy or free movement of the molds in their passage underneath the mud-mill.

A represents a case or box, which may be of rectangular form, and in which a shaft, B, is placed centrally and vertically, said shaft being provided with radial arms a , and having at its lower part, just above the bottom b of the case or box, four arms, C, which are slightly inclined from a horizontal plane, and one slotted transversely to form slots c , the outer ends of which just clear the bottom b of the case or box. In the bottom of the case or box A there is a grating, D, through which the clay is forced, the spaces between the bars of the grating being equal in area to the compartments of the brick-molds into which the clay is forced. This grating is the same as those hitherto used in this class of machines, and therefore does not require a particular description. The arms C work over the grating as the shaft B is rotated, the arrow in Fig. 2 indicating the direction of the rotation. The case or box A stands upon a rectangular box, E, in which there is placed a frame, F,

having a series of rollers, G, fitted in it, said rollers having a transverse position relatively with the box E and directly behind the rollers G. In the same frame F there are placed a series of short rollers, H, the latter being at right angles with G, back of the grating D, and in line with a hole or aperture, e, in the side of box D. The frame F is supported at one end by a rod, I, and at the opposite end by wedges J, by adjusting which the portion of the frame F containing the rollers may be raised or lowered, as desired. In the box E, near one end and below the rod I of the frame F, there is a transverse shaft, K, having a spring, L, attached to it, which projects up back of the rod I, said shaft also having two arms, M M, attached to it, the upper ends of which have bars, N N, connected to them by pivots d . These bars N N work through holes e , made in a cross-bar, O, underneath the mud-mill. (See Figs. 1 and 3.) The spring L has a tendency to keep the bars N N forced backward, so that they will not extend through the holes e . To one end of the shaft K there is attached a lever, P.

The operation is as follows: The clay is thrown in the mud-mill A and properly tempered and ground by the action of the arms a , the shaft B being rotated by horse or other convenient power. The arms C force the clay through the grating D and into the molds S, the empty ones being inserted through the aperture C on the rollers H underneath the mud-mill A. The molds are shoved underneath the grating D by actuating the shaft K through the medium of the lever P, the bars N N shoving the molds, and it will be seen that as an empty mold is shoved underneath the grating a filled mold will be shoved out from underneath the mud-mill, the tops of the molds being scraped smooth by adjusting the frame F through the medium of the wedges J to such a height that the tops of the molds will be against the under side of the mud-mill.

The arms C, in consequence of being slotted, as shown, are prevented from drawing the clay around with them, and they force the clay down through the grating D and into the molds in a much more efficient manner than they otherwise would. The rollers G H insure the free movement of the molds S, obviating much friction.

Having thus described my invention, I claim as new and desire to secure by Letters Patent—

1. The slotted inclined arms C, attached to the shaft B, for the purpose of forcing the clay through the grating D, and without drawing the clay around in the mud-mill A, substantially as set forth.

2. The frame E, provided with the rollers G H, placed within the box E, and hung upon a rod, I, at one end, and supported by wedges J J at the opposite end, substantially as and for the purpose specified.

3. The bars N N, attached to arms M M on a shaft, K, provided with a spring, L, all arranged and applied substantially as shown, for the purpose of forcing the empty molds in proper position underneath the mud-mill to receive the clay and in forcing the filled molds out from underneath the mud-mill, as set forth.

ABRAHAM WITMER.
